UNITED STATES PATENT OFFICE.

ELMIN T. BANZHAF, OF SAN FRANCISCO, CALIFORNIA, ASSIGNOR, BY MESNE ASSIGNMENTS, TO BAKER PERKINS COMPANY, INC., OF SAGINAW, MICHIGAN, A CORPORATION OF NEW YORK.

ELECTRIC IGNITION SYSTEM FOR GAS BURNERS.

Application filed December 6, 1922. Serial No. 605,155.

This invention relates to improvements in electric systems for lighting a plurality of gas burners, especially those of baking-ovens.

5 In such ovens the gas is fed to the burners under pressure, and for certain reasons which need not be gone into here, the pressure of individual burners is apt to momentarily drop, causing the fire of those burners 10 to be extinguished. With the resuming of the pressure feed, a quantity of unlighted gas will flow from the burners, which if allowed to accumulate before being reigned, is apt to cause an explosion and the wrecking 15 of the oven.

Consequently, to avoid the possibility of such a disaster, a man is employed to keep a watch over the burners all the time the oven is in operation, and to immediately 20 relight one with a torch or other means as soon as it is extinguished, which can be determined by the audible sound accompanying the extinguishing. Since some ovens have upwards of a hundred burners, and the 25 extinguishing of any one or more at a time is apt to be quite frequent, it is evident that the entire time and services of a man are necessary to attend to keeping the burners going.

30 The principal object of my invention is to eliminate the above named crude and unsatisfactory method by providing an electric ignition system which will cause igniting sparks to be constantly made adjacent each 35 burner for the entire time the oven is in operation.

A further object is to provide a system for the purpose, which, once the current controlling switch is closed, will require absolutely no attention of any character at any 40 time, barring of course an occasional inspection and replacement of any parts which may be worn or burnt out.

45 A further object of the invention is to produce a simple and inexpensive device and yet one which will be exceedingly effective for the purposes for which it is designed.

50 These objects I accomplish by means of such structure and relative arrangement of parts as will fully appear by a perusal of the following specification and claims.

In the drawings similar characters of ref-

erence indicate corresponding parts in the several views.

Fig. 1 is a perspective view of the cabinet 55 in which the spark-controlling mechanism is located.

Fig. 2 is an enlarged vertical section of the main portion of the same, showing the distributor and its operating mechanism. 60

Fig. 3 is a longitudinal view of a portion 65 of a burner, showing the sparking attachment.

Fig. 4 is an end view of the same.

Fig. 5 is a fragmentary view of the dis- 70 tributing panel.

Fig. 6 is an electrical diagram of the circuits employed.

Referring now more particularly to the characters of reference on the drawings, the 75 numeral 1 denotes a cabinet of suitable dimensions and adapted to be positioned in any desired and visible location, having a door 2 covering the entire front, with a glass panel 3 in the upper portion of the door. 80

Mounted in the cabinet behind the glass is a panel 4 of bakelite or similar insulation material, through which a centrally located shaft 5 projects, this shaft being journaled in a metal bushing 6 mounted on the panel 85 by means of screws 7. A conducting finger 8 is fixed on the outer end of the shaft (this being the end thereof nearest the glass) the outer end of this finger having a flexible brush or contact 9 adapted to engage with 90 any one at a time of a number of contacts 10 mounted on the panel 4 and arranged in a circle concentric with the shaft 5, said contacts having binding posts 11 arranged in connection therewith on the back of the 95 panel.

Another set of contacts 12, similar to the contacts 10, is mounted on the panel about a circle concentric with the shaft 5 and smaller than the circle of the contacts 10, 100 said contacts 12 being adapted to be engaged one at a time by a brush 13 projecting from one side of the finger 8, binding posts 14 for said contacts 12 being located on the back of the panel 4. The total number of contacts 10 and 12 is equal at least to the total number of burners in the oven.

The contacts 10 are so arranged with respect to the contacts 12 that no one in either

row will be in engagement with its respective finger-brush at the same time as the other brush is engaged with a contact of the other row, this being of course for the purpose of avoiding the possibility of a short circuit, as both brushes are connected to the common conducting finger.

The shaft 5 is rotated by means of an electric motor 15 mounted in the cabinet 1, the shaft of said motor having a worm 16 thereon which drives a worm gear 17 fixed on the shaft 5 but insulated therefrom.

An additional bearing member 19 is provided for the shaft, besides the bushing 6, thrust members 20 being placed on the shaft at the ends of the member 19 to prevent longitudinal movement of the shaft.

The gas burners of the oven are shown in the present instance as being metal pipes 21 having an irregular cut or slit 22 extending lengthwise thereof and from which the gas issues.

On to each pipe or burner, adjacent the beginning of the slit thereof, I secure a block 23 of the heat-resisting insulation material, such as porcelain, in which is mounted an electrode 24, similar in form to an electrode of an ordinary spark plug, which projects over the slit in the pipe, and terminates a suitable distance therefrom, so that a spark may be formed at the gap between this electrode and the pipe adjacent the slit, said pipe forming the other electrode, as will be seen.

Wires 25 lead from the individual electrodes 24 to the contacts 10 or 12, each wire being preferably enclosed in a porcelain tube 26 for that portion which is inside the oven.

The circuits and electrical devices used in the system are as follows:

40 The main lighting and power wires 27, carrying a current of 110 or 220 volts, are connected directly to the motor 28 which operates the means for creating the gas pressure, and also to the distributor motor 15, 45 a main switch 29 being interposed in the line ahead of the motor leads. Interposed in the main line beyond the motors is a step-down transformer 30, to reduce the line voltage to six volts or thereabouts. A lead 31 50 from said transformer is connected to one terminal A of a three-pole double-throw switch 32. A lead 33 from the finger 8 is connected to another terminal B of the switch 32, while the third terminal C is practically grounded, or as shown, is connected by a lead 34 to the burner pipes 21 which are themselves grounded.

55 The leads 31 and 34 are connected by the closing of the switch 32 with the primary leads 35 of a vibrating spark or induction coil of ordinary character indicated at D, the lead 33 being then connected to the lead 36 of the secondary or high tension winding of the coil.

60 The lead 33 is conductively connected to

the finger 8 by being attached to one of the screws 7 of the bushing 6, as shown in Fig. 2.

To prevent non-functioning of the system in the event that the coil D should for any reason become deranged and inoperative, a 70 duplicate coil E is provided, having leads 35^a and 36^a corresponding to the leads 35 and 36, and adapted to be coupled up with the circuits by the throwing of the switch 32 into engagement therewith. 75

The operation of the system will, it is thought, be fairly self-evident.

With the closing of the main switch 29, the motors 28 and 15 are caused to operate, the gearing between the latter and the shaft 80 5 being such that the shaft and finger 8 will be rotated about eight times per minute, so that each of the contacts 10 and 12, will be engaged an equal number of times in the same period. 85

The object of the coil D is of course to set up what practically amounts to a continuous high tension current in the lead 33, which, being distributed to the different electrodes 24 in rotation, causes sparks to be formed 90 thereat, which will instantly ignite the gas, issuing from any burner pipe should said gas have been extinguished since the previous spark was made.

Owing to the frequency of formation of 95 the sparks the duration of any such period of extinguishment will be so short that no accumulation of unburnt gas will be had, and no damage will result when said gas is reignited.

The coils, transformer and switch 32 are 100 preferably located in the cabinet 1 under the distributor, so that the entire mechanism is in a compact form and conveniently arranged.

The wires 25 from one set of contacts are 105 preferably led through a conduit 37 in the top of the cabinet, while the wires from the other set of contacts are led through a similar conduit 38 in the bottom of the cabinet. 110

From the foregoing description it will be readily seen that I have produced such a device as substantially fulfills the objects of the invention as set forth herein.

While this specification sets forth in detail 115 the present and preferred construction of the device, still in practice such deviations from such detail may be restored to as do not form a departure from the spirit of the invention, as defined by the appended claims. 120

Having thus described my invention, what I claim as new and useful and desire to secure by Letters Patent is:

1. In combination with a plurality of electrically connected gas burners, an electrode 125 for each burner terminating adjacent the same and insulated therefrom, a circuit in which said burners and electrodes are interposed, and automatically controlled continuously operated means for closing the circuit 130

to the electrodes in rotation and at constantly recurring intervals.

2. In combination with a plurality of electrically connected gas burners, an electrode for each burner terminating adjacent the same and insulated therefrom, a circuit in which said burners and electrodes are interposed, another circuit, the current in which

operates to induce a high tension current in the first named circuit, and automatically controlled electrical means operated by said first circuit for closing the circuit to the electrodes in rotation and at constantly recurring intervals.

In testimony whereof I affix my signature.

ELMIN T. BANZHAF.
